CROSSING SAFETY HAZARD

Filed Nov. 7, 1930

UNITED STATES PATENT OFFICE

CLYDE S. TIEBETTS, OF INDIANAPOLIS, INDIANA

CROSSING SAFETY HAZARD

Application filed November 7, 1930. Serial No. 494,079.

This invention relates to the art of controlling vehicular traffic at intersections of traffic lanes. It is the primary object of the invention to provide physical means whereby 5 vehicles will be required to approach danger zones at relatively low speeds so as to have the vehicles under control whereby they may be stopped quickly to avoid collision with other vehicles that may cross the line of 10 travel.

Other important objects reside in the provision of means that will require little or no costs of upkeep; that may be installed at comparatively low costs; and that may be applied 15 to roadways and crossings already constructed.

These and other objects will become apparent in the following description of the invention, with reference being made to the accompanying drawings, in which

Fig. 1 is a diagrammatic plan view of the intersection of two roadways with my invention applied thereto;

Fig. 2, a vertical section on the line 2—2 25 in Fig. 1; and

Fig. 3, a front elevation of an indicating signal.

Referring to the drawings, in which like characters of reference indicate like parts 30 in the several views, the roadway 10 is here shown as crossing the roadway 11 at right angles. On each side of the roadway 11 a suitable distance therefrom, for example 20 feet in one particular case back from the 35 edge of the roadway 11, I form directly in the roadway the platforms 12, 13 and 14, 15. The platform 13 is positioned in the direct line of travel of vehicles on the right hand side of the road and has a width at the end 40 A of approximately 42 inches, which will permit the wheels of vehicles to straddle the platform and the height of the platform is in the neighborhood of 5 inches so as to provide clearance thereover for the axles of the 45 vehicles. The platform is preferably tapered from the end A to the opposite end, for example where the platform is 8 feet long, to a width of 36 inches.

This narrow end is preferably inclined 50 from the level of the roadway to the upper

surface of the platform for a linear distance of about 18 inches. The end A is preferably notched out to have an incline 16 at an angle of approximately 45 degrees. The platforms 12, 14 and 15 are identical in shape and size 55 with the platform 13, the platform 12 being mounted on the other side of the roadway 10 adjacent the platform 13 whereby oncoming vehicles will approach the platform 12 from its narrower end. The platforms 14 60 and 15 are each positioned in the line of travel on each side of the roadway 10 to have their narrow ends directed toward the roadway 11. In the same manner similar platforms 17, 18 and 19, 20 are positioned respectively on both sides of the roadway 10 in the roadway 11 to have their narrow ends directed toward the roadway 10.

A vehicle traveling at high speed on either roadway approaching the intersection will 70 be warned of the platforms ahead by means of a signal or signboard 21 located at sufficient distance back of the intersection to permit the vehicle to be brought down to a speed such that the vehicle may be guided 75 safely across the platforms. To prevent vehicles from passing between the platforms such as between platforms 12 and 13, a block 22 is fixed in the roadway on a line midway between the two platforms and back thereof 80 a distance. This block is preferably of a height not to exceed 18 inches so that it will not interfere with overhanging truck bodies and is also preferably provided with a reflector 23 so as to render the block visible at 85 night by reflection from the headlights of the oncoming vehicle.

Should a vehicle be of a type having less than the standard tread, the wheels on one side of the vehicle may pass up the incline 90 16 and the other wheels remain on the roadway so that the vehicle may pass on over the platform. Since the dimension of the platforms at their greatest width approaches the clearance between the wheels of a standard vehicle, it will require a slow approach thereto to insure that the wheels will straddle the platform so that by the time the vehicle arrives at the intersection, it has a speed that 95 will permit its being stopped quickly to pre- 100

vent collision with vehicles approaching from either the left or the right on the roadway. These platforms forming the hazards over which the vehicles must travel, are preferably made of concrete so as to be durable and to be of such weight to remain in place.

While I have here shown and described my invention in the one form as now best known to me, it is obvious that structural variations may be made from that form without departing from the spirit of the invention, and I, therefore, do not desire to be limited to that precise form, nor any more than may be required by the following claims.

15 I claim:

1. A roadway vehicular traffic regulating hazard comprising a platform having a width approaching the tread of vehicles but permitting lateral clearance of the wheels 20 when the platform is straddled by vehicles, and having an appreciable height limited to provide clearance between it and the underside of the vehicles, said platform being tapered from said width to an opposite end, 25 said opposite end being sloped.

2. A roadway vehicular traffic regulating hazard comprising a platform having a width approaching the tread of vehicles but permitting lateral clearance of the wheels 30 when the platform is straddled by vehicles, and having an appreciable height limited to provide clearance between it and the underside of the vehicles, said width being at one 35 end of the platform, said end being substantially perpendicular and having a central inclined runway through the end up onto the top of the platform.

3. A roadway vehicular traffic regulating hazard comprising a platform having a width approaching the tread of vehicles but 40 permitting lateral clearance of the wheels when the platform is straddled by vehicles, and having an appreciable height limited to provide clearance between it and the underside of the vehicles, said width being at one end of the platform, said end being substantially perpendicular and having a central inclined runway through the end up onto the top of the platform, said platform 45 being tapered to an opposite inclined end having less width than the first end.

In testimony whereof I affix my signature.

CLYDE S. TIBBETTS.
